UNITED STATES PATENT OFFICE.

VICTOR E. LANE, OF DETROIT, MICHIGAN.

ELECTRIC HAMMER.

1,278,359.

Specification of Letters Patent. Patented Sept. 10, 1918.

Application filed August 6, 1917. Serial No. 184,619.

To all whom it may concern:

Be it known that I, VICTOR E. LANE, a citizen of the United States of America, residing at Detroit, in the county of Wayne 5 and State of Michigan, have invented certain new and useful Improvements in Electric Hammers, of which the following is a specification, reference being had therein to the accompanying drawings.

10 This invention relates to electric hammers in which a rotative striking member is driven by an electric motor and is adapted to deal a rapid succession of blows to a reciprocating tool.

15 It is the object of the invention to provide a striking member directly mounted upon the motor shaft and embracing the motor so as to produce a simple, compact and readily assembled device.

20 Further objects are to provide for ready removal and substitution of the impact portions of the striking member when the same are worn excessively, and to provide for transmitting the re-actions from the hammer blows to the casing of the tool rather than to the shaft upon which the striking member is mounted.

25 The provision of a member interposed between the striking member and the tool and provided with a replaceable impact portion is a further feature of the invention.

In the accompanying drawings of the invention:

Figure 1 is a view in side elevation of the 30 electric hammer, a portion of the casing thereof being broken away to disclose interior construction;

Fig. 2 is a longitudinal sectional view taken upon the line 2—2 of Fig. 1; and

35 Fig. 3 is a cross-section through an extension of the casing which carries the tool-engaging member, the section being taken on line 3—3 of Fig. 1.

The reference characters 1 and 2 respectively denote members forming a two-part cylindrical casing having an extension comprised by parts 3 and 4 respectively integral with the members 1 and 2. Centrally within said casing there is mounted a shaft 5, the 40 extremities of which are respectively journaled in bearings 5' formed one upon each of the members 1 and 2. Upon said shaft is mounted the stator 6 of an electric motor, the field coils 7 of which are wound upon 45 cores 8 projecting from a yoke 9, which yoke is formed upon an annular flange or web

10 projecting concentrically from the member 1 of the casing. The striking member is mounted fast upon the shaft 5 at one side of the motor, said member comprising a 50 spider 11, a ring 12 integrally carried by the outer extremities of the spider arms and a plurality of impact members in the nature of rollers 13 parallel to the shaft and equidistantly set into the ring 12 so as to 55 project outwardly beyond the periphery of said ring. Preferably the portion of each of said rollers which is recessed within the ring 12 will be somewhat greater than the projecting portion so that the roller may 60 be withdrawn only by endwise displacement. The outer extremities of the spider arms 11 are laterally bent so as to overhang the motor and the ring 12 surrounds the motor in a spaced relation to the yoke thereof. 65 Thus the motor is partially embraced by the striking member and the impact devices are located centrally of the casing without interfering with the central location of the motor. 14 is the tool to which the striking 70 member is adapted to transmit its blows, said member being inserted in a tubular socket 14' centrally formed in the extension 75 3 and 4. Between said tool and the striking member there is interposed a longitudinally 80 slidable rectangular member 15 bearing at one extremity upon the end of the tool and carrying at its other extremity a recessed 85 impact roller 16 similar to those which are carried by the striking member.

90 Handles are provided for both hands of the operator, one of said handles 17 projecting laterally from the casing and the other 18 being extended between standards 19 on top of the casing. Between the handle 18 95 and the bolt 20 which carries said handle there is interposed a bushing 21 of yieldable material which will serve to absorb to some extent the shocks transmitted in operation from the device to said handle. Adjacent the path of the impact members 13 of the striker the casing is lined with a hardened steel ring 22 with which said impact members have rolling contact. By this arrangement the shocks or re-actions resulting 100 from the hammer blows are transmitted through a number of the members 13 direct to the casing and are not concentrated upon the shaft or the bearings thereof.

105 In the operation of the above-described device, pressure of the tool upon the work will act to displace the member 15 inwardly

so as to shift its impact member 16 into the path of the rapidly rotating members 13. At each contact of a member 13 with the member 16 the part 15 and the tool 14 will 5 be thrust violently outward so as to strike a solid hammer blow. Since the device is held under constant pressure against the work 10 the member 15 will be shifted inwardly after each blow so as to again dispose the member 16 in the path of the members 13. When the tool is not in use and the implement is held substantially in the position illustrated, the block 15 will drop down of its own 15 weight so as to withdraw the member 16 from the path of the members 13. Thus without any manipulation other than withdrawing the device from the work and holding it in its natural position, the transmission of hammer blows to the tool may be 20 discontinued without stopping rotation of the motor.

In Fig. 3 there is illustrated a slight modification of the invention consisting in subjecting the member 15 to the action of a coiled spring 23 which tends to force said member inwardly and return the member 16 into the path of the members 13 after each hammer blow.

What I claim as my invention is:

- 30 1. A hammer comprising a casing, a motor therein comprising a stator and a rotor, and a striking member rotatively driven by and partially embracing said motor.
2. A hammer comprising a casing, a motor 35 therein and a striking member rotatively driven by the motor and having an annular outer portion surrounding the motor.
3. A hammer comprising a casing having an annular interior flange, a motor within 40 the casing having its field yoke formed by a lateral projection from said flange, and a striking member rotatively driven by the motor and having an annular outer portion surrounding said field yoke.
- 45 4. A hammer comprising a casing, a motor therein, a striking member having an annular portion surrounding the motor and having a plurality of impact members carried by said annular portion and having an engagement with the casing for transmitting re-actions of the hammer blows directly thereto.
- 50 5. A hammer comprising a casing having

an interior annular groove, a motor in said casing, and a striking member driven by 55 said motor having an annular portion engaged in said groove and carrying a plurality of impact members retained by the walls of said groove against lateral displacement.

60 6. A hammer comprising a casing, a motor therein, a striking member rotatively driven by said motor, and a plurality of impact rollers mounted peripherally in the striking member and projecting outwardly therefrom, said rollers being restrained against lateral displacement by the walls of the casing.

7. A hammer comprising a portable casing, a motor mounted in said casing, a striking member within the casing driven by said motor, a member radially carried by the casing to receive the hammer blows, and a handle upon the casing in diametrically opposed 70 relation to said member.

8. A hammer comprising a portable casing having a substantial radial extension, formed with a radial bore and constituting a tool socket, a striking member mounted within said casing, a plurality of impact 80 members rotatively carried by the striking member, a sliding member mounted in the inner portion of said extension to receive the hammer blows, and a handle upon said casing in a diametrically opposed relation 85 to said extension.

9. A hammer comprising a casing, a motor therein including a field yoke, means projecting inwardly from the peripheral wall of said casing supporting said field yoke, 90 and a striking member rotatively driven by the motor and having an annular outer portion surrounding said field yoke.

10. A hammer comprising a cylindrical casing having a radial extension, a motor 95 within said casing in a symmetrical relation to the axis of said extension, a member slidably mounted in said extension, and a striking member within the casing rotatively driven by said motor, and having an 100 annular portion surrounding the motor engageable with said sliding member to actuate the latter outwardly.

In testimony whereof I affix my signature.

VICTOR E. LANE:
